CLAIM

The ornamental design for a light bar as shown and described.

DESCRIPTION

FIG. 1 is a top front right side perspective view of a light bar showing our new design;

FIG. 2 is a bottom back left side perspective view thereof;

FIG. 3 is a front view thereof;

FIG. 4 is a rear view thereof;

FIG. 5 is a top view thereof;

FIG. 6 is a bottom view thereof;

FIG. 7 is a right-side view thereof; and,

FIG. 8 is a left side view thereof.

The broken lines in the drawings depict portions of the light bar which form no part of the claimed design.

1 Claim, 4 Drawing Sheets
